UNITED STATES PATENT OFFICE.

ELISHA P. TEETERS, OF ALLIANCE, OHIO.

MAIL-BAG.

SPECIFICATION forming part of Letters Patent No. 256,408, dated April 11, 1882.

Application filed February 23, 1882. (No model.)

To all whom it may concern:

Be it known that I, ELISHA P. TEETERS, of Alliance, in the county of Stark and State of Ohio, have invented certain new and useful 5 Improvements in Mail-Bags; and I do hereby declare the following to be a full, clear, and exact description of the invention, such as will enable others skilled in the art to which it pertains to make and use the same.

10 My invention relates to an improvement in mail-bags, and more particularly to that class thereof which are adapted to be closed by folding their open ends and attaching the same to staples arranged to be engaged with a suitable lock, the object of the present invention being to provide a mail-bag which shall combine simplicity of construction and ease of operation with durability and efficiency in use.

In the accompanying drawings, Figure 1 is 20 a view in side elevation of a mail-bag constructed in accordance with my invention, the bag being open. Fig. 2 is a similar view of the upper end of the bag, one corner thereof being closed. Fig. 3 is a view of the upper end 25 of the bag, both corners being folded. Fig. 4 is a view of the bag as it appears when closed and locked. Fig. 5 is a view in perspective of my improved bag in its adjustment for filling with mail-matter, and Fig. 6 is a modification 30 of my improved bag.

A is a mail-bag constructed of leather, canvas, or any other suitable material. The upper ends of the sides B and C thereof are adapted to be folded and attached to staples D, secured 35 to the side B, said staples being arranged to engage with a lock, E, attached to the outer face of the side C. The upper ends of the said sides B and C are also provided each with four horizontal and two vertical slots, F and G, respectively, the horizontal and vertical slots of one side being arranged to register with the corresponding slots of the other side. These slots, with the exception of two vertical slots, G, of the side C, are provided with suitable metallic eyelets, I. The said lock E is permanently 40 secured to the outer face of the side C of the bag. It may be of any approved form of construction so long as it is adapted to receive and engage with the staples D after they have 45 had the eyelets of the appropriate slots attached to them, the said staples entering the

lock through the vertical slots G of the side C. The lock E is also preferably adapted to receive a removable slide, J, to indicate the destination of the bag. Grommets K, inserted in 55 the sides of the bag, are designed to adapt it to be suspended from appropriately-formed hooks L, attached to the rack-rods M, as shown in Fig. 5 of the drawings. That portion of the bag lying between the two staples D is perfor- 60 ably studded with rivets or bosses N for the purpose of imparting sufficient rigidity to the leather or canvas at this point to hold the staples erect. Loops O, secured to the ends of the bag in the usual manner, are designed to 65 enable it to be readily handled.

In Fig. 5 of the drawings the bag is shown in its adjustment for filling, such adjustment being obtained by folding the ends of the sides B and C inward, and by suspending the bag 70 between a rack constructed of two rods, M, by means of hooks L, attached to the said rods and inserted in the grommets K. In turning the ends of the sides inward, as shown, the lock E and its indicating-slide will be brought 75 in full view, so that when several bags are suspended side by side they are readily distinguished from each other, thus facilitating the distribution of mail-matter through them.

In closing the bags the corners of the upper 80 ends of the sides B and C are first folded, as shown in Figs. 2 and 3 of the drawings. This manipulation will engage the eyelets of the outer horizontal slots with their respective staples. It will also register the eyelets of the 85 central horizontal slots with the vertical slots G in line with the staples E, upon which the end of the bag is now pressed, causing the staples to pass through the eyelets last mentioned and to enter the lock E through the slots 90 G of the side C of the bag. In the lock the staples will be engaged by suitable lock-bolts, by which they will be retained until the same are retracted by the key.

In Fig. 6 of the drawings an old-style bag is 95 shown as provided with my invention. This is effected by cutting off the ends of the bag and then securing a belt, P, to it, the said belt being adapted to be closed and locked in accordance with the invention shown in the other 100 figures of the drawings. In applying the belt P the bag should be cut away, as indicated by

the dotted line R, to avoid any extra thicknesses of leather or canvas.

What I claim is—
A mail-bag, the sides of which are of the same length, one side being provided with four horizontal and with two vertical slots, and with two staples which are secured to its outer face and located respectively below the said slots, the other side of the bag being provided

with the same number of horizontal and vertical slots, substantially as set forth.

In testimony whereof I have signed this specification in the presence of two subscribing witnesses.

ELISHA P. TEETERS.
